PESSARY

George Stubbs, Los Angeles, Calif.

Application April 14, 1950, Serial No. 155,870

1 Claim. (Cl. 128—127)

1

This invention relates to improvements in pessaries.

Devices of this character have legitimate uses for the correction of retro-displacements of the cervix and prolapsus of the uterus. They also may be used readily for correction of post partum displacements.

A primary object of the invention is to provide an improved pessary consisting essentially of a circular ring-like body which can be folded on a single diameter and which otherwise than on the mentioned diameter is relatively rigid. With such a construction the pessary may be inserted in a folded or collapsed condition and allowed to return after insertion into a substantially flat or planar condition. When the body has thus been returned to its normal condition it may be rotated ninety degrees from its position during insertion so that the fold line or fold diameter on which the pessary is readily foldable is disposed in a transverse direction. In this position the pessary is relatively rigid or stiff when considered in a direction extending longitudinally of the vaginal cavity. When it is desired to remove the pessary the pessary may be rotated ninety degrees so that its fold line or fold diameter will be disposed coincident with the length of the vaginal cavity and the pessary can then be folded and readily withdrawn.

Another object of the invention is to provide a pessary having the above mentioned characteristics wherein the inner surface of the rubber covering of the pessary is notched. The notches are located where the pessary may be readily folded and contribute to the ease with which the pessary can be folded at the desired points and also function as indicators that can be readily felt to determine the position of the pessary and the location of its fold diameter.

A further object of the invention is to provide an improved pessary and method of making the same whereby a pessary can be very easily and quickly constructed with a minimum amount of labor and material and which possesses the advantages that it may be sterilized.

With the foregoing and other objects in view, which will be made manifest in the following detailed description and specifically pointed out in the appended claim, reference is had to the accompanying drawings for an illustrative embodiment of the invention, wherein:

Figure 1 is a top plan view, parts being broken away and shown in horizontal section of a pessary embodying the present invention;

Fig. 2 is a vertical section through the same

taken substantially upon the line 2—2 upon Fig. 1;

Fig. 3 is a perspective view of the pessary shown in Fig. 1, the pessary being shown in its folded or collapsed condition;

Fig. 4 is a top plan view of an alternative form of pessary embodying the present invention, parts being broken away and shown in horizontal section;

Fig. 5 is a sectional view taken substantially upon the line 5—5 upon Fig. 4; and

Fig. 6 is a perspective view illustrating the pessary in its folded or collapsed condition.

Referring to the accompanying drawings 15 wherein similar reference characters designate similar parts throughout, the pessary illustrated in Figs. 1, 2 and 3 consists of two opposed approximately semi-circular sections of solid metal wire. These sections are indicated at 10 and 11. They are formed of a relatively stiff malleable metal, the intention being that the metal possess little if any resiliency so that if necessary the wire can be bent forcibly to a desired shape and when so bent it will remain in the bent shape. 20 The sections 10 and 11 have their ends disposed in opposition to each other but are spaced from each other forming gaps 12 and 13. A single section of rubber tubing is slipped onto these sections and the ends of the rubber tubing are 25 brought together as indicated at 14, intermediate the ends of one of the wire sections and are cemented or vulcanized together. The internal diameter of the rubber tubing is normally smaller than the diameter of the wire used to form the 30 wire sections 10 and 11 so that in slipping the rubber onto the wire sections it is necessary to stretch the rubber to a considerable extent. When the rubber has been slipped onto the wire it will, of course, inherently tend to contract 35 thereabouts and this feature is relied upon to frictionally hold the wire sections within the rubber against shifting or against displacement and thus maintain the gaps at 12 and 13. The inner side of the rubber, when it has been thus 40 assembled with the wire sections, is buffed out or notched as indicated at 15 and 16. These notches are disposed opposite the gaps 12 and 13 between the ends of the wire sections. The notches perform two functions. One function 45 is to reduce the thickness of the rubber opposite the gaps 12 and 13 rendering the rubber more readily bendable at the gaps and, in the course of folding the pessary into a position as shown in Fig. 3, the notches enable the rubber at the 50 sides of the notches to be easily brought together

without involving compression of the rubber if the notches 16 are not present. On folding the pessary, that rubber which would be on the inner sides of the gaps 12 and 13 would be highly compressed and the rubber on the outer sides of the gaps 12 and 13 would be severely stretched or placed under tension. The presence of the notches avoids this compression on the inner sides of the ring and voids the high tension or stretching on the outer sides of the ring opposite the gaps 12 and 13.

The second function performed by the notches 15 and 16 is that of serving as an indicator as to the location of the gaps 12 and 13. These gaps, which are not occupied by stiff wire, locate the fold line or diameter on which the pessary can be readily folded or collapsed.

While the sizes are not critical, typical sizes employed are to use wire for the sections 10 and 11 formed of mild or malleable steel having a diameter of approximately $\frac{3}{16}$ inch. The rubber tubing employed has an outside diameter of approximately $\frac{5}{8}$ inch and, as above explained, the normal internal diameter should be slightly smaller than the diameter of the wire so that it is necessary to stretch the rubber slightly in slipping it onto the wire and the rubber will then contract on the wire sections and hold them against displacement which might close the gaps 12 and 13.

When the pessary is of circular form, as shown in Figs. 1 to 3, it may be inserted in the folded or collapsed condition and then allowed to return to its normal or planar condition due to the resiliency of the rubber surrounding the gaps 12 and 13. In this position the pessary can then be rotated through ninety degrees from its position of insertion so that the fold line or fold diameter across the gaps 12 and 13 is positioned transverse to the vaginal cavity. In this position the pessary is relatively stiff and rigid considered in a direction extending longitudinally of the vaginal cavity or across a diameter that is ninety degrees from the diameter across the gaps 12 and 13. In removing the pessary it is again rotated either forwardly or reversely ninety degrees to position the fold line or fold diameter across the gaps coincident with the length of the vaginal cavity. This position can be determined readily by feeling for the location of the notches 15 or 16 whichever is disposed forwardmost.

In the construction shown in Figs. 4, 5 and 6, the pessary is in the form of an ovate ring-like body likewise composed of two opposed or complementary wire sections 20 and 21. These sections are formed of solid malleable metal wire and have their opposed ends close to each other

but nevertheless in spaced relation so as to leave the gaps 22 and 23. The rubber covering 24 consists of rubber tubing, the internal diameter of which is slightly smaller than the diameter of the wire used to make the wire sections so that in applying the rubber covering it is necessary to slightly stretch the rubber. The rubber when in position will contract on the wire sections and frequently hold them against displacement. The ends of the rubber tubing are brought together as at 25 and are cemented or vulcanized. In this form of construction the pessary can be readily folded or collapsed upon a line connecting the gaps 22 and 23 but will normally return due to the resiliency of the rubber to its normal position as shown in Figs. 4 and 5. In this form of construction, while the interior surfaces of the rubber covering could be notched opposite the gaps 22 and 23 to facilitate the bending of the rubber, as above explained, the notches are not necessary to serve as indicators inasmuch as the shape of the pessary itself determines its position in the vaginal cavity. Consequently the notches are not shown in Figs. 4, 5 and 6.

The improved pessaries are highly advantageous in that they may be easily constructed with a minimum amount of labor and material. Also they may be easily sterilized.

Various changes may be made in the details of the construction without departing from the spirit and scope of the invention as defined by the appended claim.

I claim:

A pessary comprising two complementary sections of solid malleable wire bent to the shape of opposed sides of the pessary, each section having its ends slightly spaced from but arranged in opposition to the ends of the other section, and a rubber tube having a normal internal diameter smaller than the diameters of the wire sections stretched over said sections and enclosing the same whereby the pessary may be folded between the ends of the sections by flexing that portion of the rubber tubing which bridges the gaps between the ends thereof and the sections will be held against shifting within the tubing by reason of the contracting engagement of the rubber upon the wire sections.
